UNITED STATES PATENT OFFICE.

JOHN FRANCIS BOORAEM, OF GREENWICH, CONNECTICUT.

NOZZLE FOR BATHS.

1,240,411.

Specification of Letters Patent. Patented Sept. 18, 1917.

Application filed July 8, 1912, Serial No. 708,216. Renewed March 18, 1916. Serial No. 83,964.

To all whom it may concern:

Be it known that I, JOHN FRANCIS BOORAEM, a citizen of the United States of America, residing in Greenwich, in the county of Fairfield and State of Connecticut, have invented certain new and useful Improvements in Nozzles for Baths, of which the following is a specification.

The object of the invention is to provide means whereby the impurities, dirt, etc., gathering at the top of the bathing water may be flushed out from the plunge-bath without necessarily removing the entire quantity of water in the plunge. For this purpose my invention consists of an improved water-inlet or nozzle whose orifice may be varied so as to regulate the flow of water and thereby cause the stream to be thrown a variable distance from the inlet-nozzle so as to force the gathering impurities and follow the same until they have been ejected.

My invention further furnishes an inlet adjustable from full inlet pipe size (permitting full capacity of delivery pipe for quick filling) to reduced inlet size for fountain service and display effect.

In the accompanying drawings,

Figure 1 is a vertical central longitudinal section through one form of my improved nozzle, showing the means used to vary the orifice of the same.

Fig. 2 is a front-view of such nozzle.

Fig. 3 is a longitudinal section of a plunge bath with the nozzle of Figs. 1 and 2 applied thereto, and indicating flushing and skimming of a full plunge.

Fig. 4 is a plan view of such a plunge bath, showing the fanning out of the flushing stream or spray under different adjustments of the nozzle on either full or empty tank.

Fig. 5 is a longitudinal section of the plunge bath showing at the right side the upward throw of stream for display, and at the other side the downward throw of stream for the purpose of cleaning the sides and bottom.

Similar characters of reference indicate corresponding parts throughout the various views.

Referring to Figs. 1 and 2 of the drawings, 10 designates the so-called inlet block, generally made of terracotta, which forms part of a complete top finish or capping sys-

tem (shown in Figs. 3, 4 and 5) as now almost universally used for plunge-baths. To this block a bushing or casing 11 is secured in a suitable opening, as by means of bolts 12, the aperture of the bushing receiving the improved nozzle 13, against the outer surface of which a washer or gasket 14 is pressed by a follower or cap 15, adjusted and held by screws 16. The clamping action of the gaskets 12^a and 14 hold the nozzle 13 in position and preserve a watertight and expansion joint.

My improved inlet-nozzle 13 has its median line arranged flush with the normal water-level in the bath, that is, flush with the water level at the top of the life rail L and when the nozzle is open as shown on drawing, the water flows into the bath and produces a current of such a character at the surface when the tank is full as to flush out floating impurities uniformly from the surface, sweeping the top surface of the plunge as was previously done both with an ordinary hose and water or also by dragging a rope on the surface, both of which methods are inefficient and laborious. For this purpose and to give flexibility to the inlet stream an adjustable nozzle is provided, the orifice of which may be changed so as to throw a stream of water at greater and greater distance from the nozzle, by decreasing the distance between the discharge nozzle plates 18 and 18^a, thereby decreasing the area of the discharge opening. The flaring nozzle 13 is rectangular in cross section and is provided at its inner smaller end with a contracted inlet adapted for connection by means of bolts 12^a or otherwise with a pipe section 17 or other water supply. The pipe section 17 is connected with a suitable supply pipe S and is tapered toward said inlet. The deflecting delivery plates or jaws 18 and 18^a are pivoted on pins 19 and 19^a within the flaring mouth of the nozzle 13 at the smaller end thereof in front of the inlet 13'. These plates are provided with fan-shaped radiating vanes or depressions 18^b to assist in flaring the stream at the discharge. In the fully open position the two plates will lie horizontally and parallel with each other with their ends in line forming an outlet area equal to or greater than the inlet pipe, thereby giving a free discharge. Externally of the nozzle 13, arms 20, 20^a are secured

100
105

rigidly to trunnions. To these arms, threaded collars or nuts 21, 21^a are pivoted to swing about horizontal axes, the threads running in opposite directions, that is, the threads 5 being respectively right and left. With these nuts are engaged the oppositely threaded end portions of a screw 22, the central portion of which is journaled in a block 23 but held in any suitable manner against sliding vertically relatively to said block, but 10 in a manner to permit free horizontal movement. This block with its pivotal action permits the ends of the plates to change their position in respect to each other. When 15 in horizontal position the ends of the plates are equally disposed, when in upward direction the upper plate has its end extending beyond the end of the lower plate, and when in downward position the lower plate has its end extending beyond the end of the upper plate. The block 23 is provided with trunnion ends 23^a movable along slideways or guides 24^a of a lever 24 fulcrumed at 24^b. The other end of the lever is provided with 20 a worm sector 24^c engaged by a worm 25 secured to a vertical shaft 26 adapted to be turned by means of a key 27. The shaft 26 is thus adapted for manual operation to rock the lever 24 and at the same time swing the 25 plates 18, 18^a on their pivots, without changing the previously set distance between said plates. By turning the screw 20^a, both plates 18, 18^a are moved simultaneously either toward or from each other, according to the 30 direction of rotation, so as to contract or enlarge the outlet of the nozzle, thus increasing or diminishing the distance to which the stream is thrown. By turning the key 27, the stream may be thrown upward or downward 35 at various angles and bring its point of impact with the surface of the water nearer to or farther from the nozzle, so that it will reach different portions of the water surface in the bath (see Figs. 4 and 5) and by a gradual motion of said key, the jet or stream 40 may be caused to exert an increased propelling action on the surface layer of the water, so as to skim off this surface layer, and by following it up to the end of the tank 45 force it into the gutter G all around the tank, as shown at M in Fig. 3. Figs. 4 and 5 show that nozzles of the character herein 50 described may be provided at both ends of the plunge bath, and Fig. 5 also shows how 55 the jet may be thrown against the bottom and sides of the bath, at varying distance from the end, to clean out the sides and bottom of tank when empty. Figs. 3 and 5 further 60 illustrate the customary life-rail L, the gutter G, and the discharge pipe or overflow pipe D.

The active or inner surfaces of the plates 18, 18^a may be given a step-like formation 65 by vanes 18^b as shown best in Fig. 2 to flare the water delivery.

Various modifications may be made without departing from the nature of my invention, as set forth in the claims.

Having thus described my invention, I claim as new and desire to secure by Letters Patent:

1. A flaring rectangular nozzle having an inlet at its inner small end adapted for connection with a water supply pipe, delivery jaws pivoted in said nozzle at the smaller 75 end thereof in front of said inlet, means for swinging said jaws in unison for adjusting them at varying inclines, and means for swinging said jaws toward and from each other for varying the size of the discharge 80 orifice.

2. A flaring rectangular nozzle having an inlet at its small end adapted for connection with a water supply pipe, delivery jaws pivoted in said nozzle at the smaller end 85 thereof in front of said inlet, the adjacent faces thereof having radiating depressions which assist in flaring the stream at the discharge, means for swinging said jaws in unison for adjusting them at varying inclines, and means for swinging said jaws toward and from each other for varying the 90 size of the discharge orifice.

3. A flaring rectangular nozzle having an inlet at its inner small end adapted for connection with a water supply pipe, delivery jaws pivoted in said nozzle at the smaller 95 end thereof in front of said inlet, the adjacent faces of said jaws being stepped from the center toward the side walls of the nozzle, means for swinging said jaws in unison for adjusting them at varying inclines, and means for swinging said jaws toward and from each other for varying the size of the 100 discharge orifice.

4. The combination of a flaring nozzle, hinged plates in the mouth of said nozzle, arms connected with the pintles of said plates and provided with screwthreaded eyes of opposite pitch, a lever pivoted between the pintles of said plates and provided with a guideway, a sliding block in said guideway, an actuating rod journaled in said block and having reverse screw-threads engaging said eyes, and means for 110 actuating said lever.

5. A nozzle comprising a flaring mouth, jaws pivoted at the small end of said mouth and adapted to spread the jet discharged thereby, means for swinging said jaws toward and from each other, and means for adjusting said jaws in unison at varying 115 inclines.

6. The combination of a flaring nozzle, hinged plates pivoted in the mouth of said nozzle, arms connected with the pintles of said plates and provided with screwthreaded eyes of opposite pitch, a lever pivoted between the pintles of said plates and provided with a guideway on one side there- 120

of and with a toothed segment on the other side thereof, a sliding block in said guideway, an actuating rod journaled in said block and having reverse screw threads engaging said eyes, and an actuating shaft provided with a worm engaging said toothed segment.

In testimony, that I claim the foregoing as my invention, I have signed my name in presence of two subscribing witnesses.

J. FRANCIS BOORAEM.
